ROTARY FUEL METERING PUMP AND
EMERGENCY MEANS INSURING FUEL
FEED UPON PUMP FAILURE

Jay A. Bolt, South Bend, Ind., and Frederick P. Jackson, Dayton, Ohio, assignors to Bendix Aviation Corporation, South Bend, Ind., a corporation of Delaware

Application April 6, 1946, Serial No. 660,248

13 Claims. (Cl. 158—36.4)

1

This invention relates to fuel metering systems, and it is primarily concerned with metering systems or devices of that type wherein fuel is supplied to a power plant or engine under pressure and is measured or metered on the basis of engine speed, usually modified by one or more operating functions or characteristics indicative of mass air flow to the engine, or air consumption. Such a device utilizes an engine-driven pump which delivers fuel under pressure to a fuel-inlet poppet valve controlled by a speed-responsive element such as a centrifugal governor rotating in synchronism with the engine and whose thrust is opposed by a metering head diaphragm. Metered fuel may be delivered through a discharge nozzle adapted to open when the metered fuel pressure attains a predetermined value, for example, 10 pounds per square inch. To obtain a compact unit, it has become common practice to utilize an inbuilt fuel pump, the pumping elements being mounted on a drive shaft or rotor in alignment with the centrifugal governor and having a drive connection with the latter.

In metering systems of this type, should the pumping elements of the engine-driven pump which delivers fuel under pressure to the governor-controlled valve seize or otherwise be rendered ineffective, the pressure in the system may be reduced to a point where the delivery of fuel to the engine will stop, and if a constant pressure fuel delivery nozzle is utilized, the fuel feed will stop entirely should the pressure drop below nozzle discharge pressure. Also in installations where the engine-driven pump drives the poppet valve governor, failure of the pump will likewise result in failure of the governor function. Again, in cases of aircraft engines or power plants utilizing an independently-controlled boost pump in series with the main engine-driven fuel pump, should the engine fail as for example during take-off, the engine-driven pump will stop, and since the latter pump may not pass sufficient fuel to overcome nozzle discharge pressure, or to permit proper functioning of the metering system, the supply of fuel to the engine is immediately cut off even though the pilot may operate the boost pump.

The primary object of the present invention, therefore, is to provide a fuel metering system of the type specified wherein should the engine-driven fuel pump fail, metering of fuel to the engine may be maintained irrespective of such failure.

Another object is to provide a safety or emergency system for fuel metering devices of the rotary pump type which, should the engine-

2

driven fuel pump fail, permits the metering system to function through operation of a boost pump or other pressurizing device controlled either automatically or by the pilot or operator.

5 A further object is to provide a fuel metering device of the rotary pump type particularly adapted for aircraft engines incorporating an emergency fuel supply and metering system which requires a minimum number of parts in addition to those already present and therefore involves only a small additional cost and little or no additional weight, and which at the same time is capable of operating over long periods of time without danger of failure and with a minimum of wear on the moving parts.

The foregoing and other objects and advantages will become apparent in view of the following description taken in conjunction with the drawings, wherein:

20 Figure 1 is a schematic diagram of a fuel feeding system incorporating the invention;

Figure 2 is a section taken substantially on the line 2—2, Figure 1;

Figure 3 is an enlarged section of part of Figure 1, particularly showing the governor chamber, by-pass valve and associated parts;

Figure 4 is a substantially central longitudinal section of the engine-driven fuel pump assembly;

Figures 5 and 6 are sections taken on the lines 30 5—5 and 6—6, Figure 4; and

Figure 7 is a detail view of the pump rotor.

Referring to the drawings in detail, the metering device comprises a main housing 10 having a portion shaped to define a fuel pump intake chamber 11 to which fuel may be supplied from a fuel tank 12 through conduit 13. A fuel pump is generally indicated at 14, and as here shown, is of the vane type comprising a rotor 15 (see Figures 4 to 7, inclusive) formed with a center bore mounting a hollow eccentric sleeve or cylinder 16, and a series of radial slots mounting pumping elements or vanes 17. The rotor is supported for rotation in a sleeve or cage 18 formed with intake and exhaust openings at an intermediate point and terminating at its opposite ends in annular portions 18', 18'' which cam the blades radially inwardly against the sleeve or cylinder 16.

50 The rotor 15 is mounted on a shaft 19 having a reduced center portion 19' which projects through the cylinder 16 and terminates at its left hand end in an enlargement 19''. The right-hand end of the rotor as viewed in Figure 4 is reduced in diameter as indicated at 20, and the shaft 19 is formed with a transverse bore 21 adapted to receive a shear pin 22 which projects

into a registering bore formed in the reduced end 20 of the rotor and provides a driving connection between the shaft and rotor.

The pump takes fuel from the chamber 11 and forces it under pressure into chamber 23 (see Figures 1, 2 and 3) defined in part, by a wall 24 having a transverse portion 24' shown as formed integral with the housing 10, said wall 24 and housing 10 having portions 25 and 26 which are contoured to receive the rotor cage 18. The chamber 23 may be aptly termed the "governor chamber." A screw 27 projects into a spline or keyway formed in the cage 18 and maintains the latter against displacement.

End caps 28 and 29, the latter being removably secured to the housing 10, support the sealing and bearing assemblies for the outer end of shaft 19, to which oil may be supplied through duct 30 forming part of the engine oiling system. A drive pinion or gear 31 is keyed on the outer end of shaft 19 and forms part of a drive connection between the pump and the engine.

The left end of the rotor 15 is reduced as at 32 and is journaled in a bushing or bearing 33, the latter in turn being mounted in bosses 34, 34' formed integral with the housing or casting 10, compare Figure 4 with Figures 1 and 3. The left end of the rotor shaft is projected outwardly and has keyed or otherwise secured thereon a bushing 35 which forms the hub portion of a cup 36 having a driving connection with a governor and poppet-valve assembly comprising an elongated valve member 37 formed with a reduced stem 37'. The valve member 37 is mounted to slide in a bushing 38 having an attaching flange 38' at its outer or left-hand end secured to the adjacent wall of the unmetered fuel chamber C, to be described, said bushing being formed with a valve seat defining a valve port 40. The reduced portion of the valve stem 37' is encircled by a spring 41 which at its left end abuts a shoulder formed on the valve stem and at its opposite end bears against the inner race of a thrust bearing 42 held in adjusted position by end nut 43.

The governor weights are indicated at 45; they are secured on pins 46 and have formed integrally therewith fingers 45' adapted to engage the thrust bearing 42 and urge the poppet valve 37 toward the open position with a force depending on the speed of rotation and the resultant centrifugal effect of the weights 45. The pins 46 are anchored in yokes 47 forming part of a hub member 48 carrying the outer race of a bearing assembly 49, the inner race of the bearing assembly being secured on the bushing 38. A driving connection between the rotor shaft 19 and governor is provided by means of lugs 51 projecting radially from the flange of the hub 48 and engaging in open slots formed in the edge of the cup 36, the latter serving to reduce turbulence of fuel in the governor chamber and to also limit the throw of the governor weights under certain conditions, as when there is no appreciable differential pressure across the metering head diaphragm, indicated at 52.

The diaphragm 52 is clamped between the radial portions or flanges of bushings 53 and 54. Bushing 53 is slidably mounted in a guide sleeve 55, while bushing 54 has connected thereto a stem 56. A cable 57 connects at one end with the stem 56 and at its opposite end with the poppet valve 37. To stiffen the cable sufficiently to prevent buckling due to idle spring thrust, a light wire spring 57' encircles the cable. An idle spring

58 engages the outer side of the diaphragm bushing 54 and applies predetermined pressure in an opening direction on the poppet valve 37 at low idling speeds to ensure sufficient metering head pressure for idling purposes.

The pump-intake or low pressure chamber 11 is separated from the governor or pump-delivery chamber 23 above the latter by the transverse portion 24' of the wall 24 mounting a two-way bypass valve assembly generally indicated at 60 and comprising a valve cage 61 which is threaded in a bore formed in said wall and has a seat 61' at its upper edge and passages 62 in the base thereof. A guide pin 63 projects upwardly from said base. A valve member 64 has a counter-bored central portion telescoped on or slidably engaging the upper free end of said pin and an outer valve element 64' adapted to engage the seat 61'. The valve member 64 is carried by a diaphragm 65 of substantially the same mean effective area as the seat 61', said diaphragm forming a movable or flexible wall of a balancing chamber 66. A spring 67 urges valve member 64 onto its seat and allows it to open when the pressure in chamber 23 exceeds the pressure in chamber 66 by some predetermined amount, dependent upon the strength of spring 67.

Means are also provided whereby should the pressure in the governor chamber 23 drop below a certain value, due for example, to failure of the engine-driven pump 14, fuel will pass from the low-pressure side (chamber 11) of said pump into said chamber 23. To afford compactness and lower costs of manufacture, a return bypass has been built into the valve assembly 60. Thus the valve member 64 is formed with a series of radial inlet openings 68 which feed into an annular passage or valve port 68' surrounding the central portion of said member, said port being normally closed by a valve member 69 urged to its seat by a spring 70 plus the pressure existing in chamber 23. As long as the engine-driven pump 14 operates normally, the pressure in chamber 23 is sufficient to maintain the valve 69 seated, and the by-pass valve 60 can then act in one direction only, viz. to relieve excess pressure from chamber 23, but should the pressure in chamber 23 drop below a predetermined value, valve 69 will open and permit fuel to flow from chamber 11 into chamber 23.

In order to provide a substantially constant pressure drop across the valve 37 and balance the various pressures in the metering system, the chamber 66 is connected by a duct or passage 71, 71' with chamber C and which may be considered the unmetered fuel chamber. Chamber 66 also communicates with chamber 11 through a restricted orifice or bleed 72 to permit complete filling of chamber 66 and relieve excess pressure developed in said latter chamber by engine heat when the engine is stopped.

When the pump is initially placed in operation and sufficient pressure is built up in the chamber 23, the valve 64 will open. When this valve opens, fuel pressure will build up in the chamber 11 to a predetermined value, whereupon fuel will pass through orifice 72 into chamber 66. Since this latter chamber is in communication with the unmetered fuel chamber C, the pressure on the top side of diaphragm 65 will be unmetered fuel pressure while that on the lower side of the valve 64 will be equivalent to that in the governor chamber 23; and the differential between these chambers 66 and 23, and hence the drop across the valve 37 will be maintained

at a substantially constant predetermined value as determined by the spring 87 irrespective of the flow of fuel delivered by the unit.

The valve generally indicated at 75, Figure 1, is an idle cut off valve; it is used to completely cut off fuel to the engine to stop the latter. This valve is provided with a stem 76 and a lever 77. The valve has a cylindrical rotary valve member 78 located in the fuel discharge conduit 79 and having a through passageway or valve port adapted to register with said conduit when the valve handle is turned to "on" position. In the position shown, the valve is open and fuel may flow through the conduit 79. The fuel discharge conduit is adapted for attachment of a suitable fuel line 79' leading in the present instance to a spray nozzle, to be described, but which may lead to any other suitable discharge device, depending upon what type of power unit is being supplied with fuel.

It will be noted that the passage or duct 71 connects with the continuation 71' thereof through a valve port in the form of a through bore 88 formed in a cylindrical rotary valve member 81 mounted on and rotatable with valve stem 76. Thus when the idle cut off valve 75 is closed, valve 81 is likewise closed and communication between the unmetered fuel chamber C and the chamber 66 is broken. The reason for this is that should the unmetered fuel pressure still be applied to chamber 66 after fuel flow is stopped and during further running of the engine due to momentum, the by-pass valve 84 would not open and dangerously high pressures in the system would result.

It is important that vapor be completely eliminated from the pressure chamber in which the governor and poppet valve assembly operate. Since fuel in vapor form is lighter than when in the liquid phase, it tends to gather in the governor chamber, due to the fact that the heavier liquid fuel is thrown outwardly by centrifugal force, where the lighter vapor reduces the specific gravity of the fuel which in turn tends to reduce the fluid resistance to movement of the governor weights and increases the effective throw of the latter, thereby increasing the metering head and tending toward a rich fuel-air ratio. If sufficient vapor collects to more than fill the spinning cup in the governor chamber, it will pass through the system and result in a lean condition of the fuel-air ratio.

A vapor elimination system which has been found highly effective takes advantage of the tendency of the vapor to centrifuge or move towards the central area of the governor chamber. Such a system is disclosed in copending application Serial No. 586,224 filed April 2, 1945, in the names of Willard F. Blakeway and Albert P. Schnaible, and assigned to the assignee of the instant invention. A unique feature of this vapor elimination system is that it acts to centrifuge air and vapor from the fuel before any of the fuel in the delivery chamber 23 is passed through the relief valve back to the low pressure side of the engine-driven pump, so that it is less likely to completely vaporlock the pump, even though the system may be operated without boost pump or tank pressurization when cruising at altitude. The spinning cup 36 which houses the governor weights is formed with a series of holes or openings 86 in the peripheral and end walls thereof, and the hub member 48 is also preferably formed with a series of similar openings 86', the lighter fuel components passing into the central area of

the spinning cup through these holes 86, 86'. From this point the vapor may pass by way of a port or passageway 87 formed in the left extremity of the rotor shaft and thence by way of discharge passages 88, 88' to an annular collecting chamber 89 formed in the boss 34. A vapor vent channel 90 communicates the annular chamber 89 with a vapor vent chamber 91, the latter being provided with a float 92 carrying a valve member 93 slidable on the lower end of a hollow depending stem provided with a port 94, said valve 93 controlling a vapor discharge passage 95 which may lead to the fuel tank or to some other suitable point such as the engine air intake. An apertured inverted cup-like member 96 provides a smooth internal wall to permit free vertical movement of the float. During periods of operation, a continuous flow of liquid and/or vapor occurs from the center portion of the governor chamber to the float chamber 91. In the absence of vapor, the liquid fuel in chamber 91 fills the latter and the float valve 93 closes the port 94. Fuel thereafter supplied to chamber 91 escapes through a passage 97 and restriction 98 to the by-pass chamber 11. Any vapor centrifuged towards the center of the spinning cup escapes through the passages 87, 88 to the annular chamber 89 and thence through the channel 90 to the float chamber 91. When there is little or no vapor or air in the float chamber 91, the valve port 94 is closed by the valve 93; but when vapor or air enters said chamber, it depresses the liquid fuel level, the float drops and the valve 93 uncovers the port 94, permitting vapor and air to escape back to the fuel tank through conduit or passage 95. As the vapor escapes, liquid fuel entering chamber 91 raises the fuel level therein and moves the float 92 upwardly to close port 94.

The fuel in chamber C may pass through a metering orifice 100 into metered fuel chamber B, Figure 1, which is in communication with the discharge conduit 79. The orifice 100 is controlled by a needle 101 connected to and regulated by a capsule or bellows 102 mounted in a housing 102', a pipe connection 103 communicating manifold pressure to said housing. As manifold pressure increases, bellows or capsule 102 is compressed, thereby retracting needle 101 from metering orifice 100, and as manifold pressure decreases bellows 102 expands, thereby projecting needle 101 into the said metering orifice. The bellows 102 is connected at its rear end to the movable end of a bellows 104, the interior of which is vented to the atmosphere at 105 and whereby the action of the manifold pressure capsule is modified by changes in atmospheric pressure and which is an index of exhaust back pressure. Unmetered fuel may also flow through a passage 106 and thence through supplemental metering orifice 107 into the metered fuel chamber B, the orifice 107 being controlled by a needle 108 connected to a temperature-responsive bellows 109 which in turn is operatively connected to a temperature-sensitive element mounted in the engine intake manifold or other point indicative of the temperature of the air flowing to the engine cylinders.

A fuel discharge nozzle is generally indicated at 110: it receives metered fuel under pressure from the conduit 79 and is adapted to open at some predetermined pressure, for example 10 pounds per square inch, and discharge fuel into an air-induction conduit 111 for supplying air to the engine, not shown. The nozzle 110 may be provided with a diaphragm chamber vented to

air-intake pressure anterior the throttle 112, so that should an auxiliary supercharger be used, the additional pressure generated in the conduit 111 will not reduce the opening pressure of the nozzle.

The fuel tank 12 has mounted in the base thereof a boost pump 116, preferably of the submerged positive-displacement or vane type, the pump being herein shown as electrically driven and controlled by a switch 117 mounted in convenient reach of a pilot or operator and connecting with the pump through line wire 118. A source of potential such as a battery is indicated at 119.

The high pressure or discharge side of the pump 116 is connected to the conduit 13 by conduit 120, and a check valve 121 permits fuel to bypass the pump 116 when the latter is idle, and also checks back-flow of fuel into the tank when the said pump is in operation and pressurizing fuel in conduit 13. A relief valve 122 determines the maximum pressure delivery of the pump 116, said valve being connected to a diaphragm 123 forming the movable wall of a chamber 124 in which a spring 125 is mounted and adapted to engage the diaphragm 123. The chamber 124 is vented to the unmetered fuel chamber C of the regulator by means of a conduit 126. The spring 125 may have a force equivalent to the drop across the poppet valve 37, for example between five and ten pounds per square inch, so that the effective pressure of the pump 116 will be sufficient to ensure ample fuel flow under all conditions of operation.

A pressure gauge 127 is provided in the pilot's compartment or other point within view of an operator, and communicates with the governor chamber 23 through pipe or conduit 128. Should the pressure in chamber 23 drop below some safe value, due to failure or faulty delivery of the engine-driven pump 14, the pilot will be immediately notified and turn on the boost pump 116.

The operation is as follows:

The fuel pump 14 may be suitably geared to the engine or power plant to be supplied with fuel and driven thereby. Rotation of the rotor shaft 19 causes the drive to be applied to the pump rotor through the shear pin 22. As the rotor rotates, fuel is drawn in through the conduit 13 from the tank 12 and into the chamber 11, from which it is forced by the rotor blades or vanes into the governor chamber 23. The relief valve 64 is set to maintain the fuel in chamber 23 at a predetermined pressure over and above the pressure in unmetered fuel chamber C, and when this pressure is exceeded, the valve 64 is opened and the excess fuel is by-passed back to the chamber 11. When the engine is operating, the rotating governor weights 45 and the idle spring 58 tend to open the valve 37 and permit fuel under pressure to pass from the chamber 23 through the valve port 40 into the unmetered fuel chamber C. The fuel flows through metering orifice 100 into the metered fuel chamber B and thence through the fuel conduit 79 to the fuel discharge nozzle 110. As soon as the metered fuel pressure attains a value equivalent to the pressure setting of the discharge nozzle, the latter opens and fuel is discharged into the engine intake conduit or other point of supply. The valve 37 will float towards open or closed position until the governor head acting on diaphragm 52 balances the force of the governor weights 45. Since the governor rotates in direct relation to

engine speed, the thrust of the governor weights is proportional to speed squared and therefore the balancing differential across the diaphragm 52 is maintained proportional to speed squared and the metering head across the metering orifice 100 is also maintained proportional to speed squared for any given position of the needle 101. Assuming a fixed area of the metering orifice 100, then flow therethrough is proportional to the square root of the pressure difference thereacross and hence is proportional to engine speed. For a constant condition of manifold pressure and exhaust back pressure, the air flow to the engine will vary in direct proportion to engine speed, and the control mechanism will correspondingly vary the quantity of fuel supplied to the engine. Since the mass rate of air flow to the engine is dependent not only on the engine speed but also upon manifold or charging pressure, air temperature and exhaust back pressure, the area of orifice 100 is controlled by needle 101; while the area of orifice 107 is controlled by the temperature responsive needle 108. Thus as the manifold pressure is varied, as by actuation of a throttle valve in the air intake conduit, or by variation in speed of a supercharger at a given throttle opening, such variations will be transferred to the chamber defined by the housing 102 and imposed on the capsule therein, the effective action of the capsule being modified by changes in atmospheric pressure through the action of bellows 104, and compensation for changes in temperature being had through control of orifice 107 by temperature needle 108.

Should the rotor of the engine-driven vane pump 14 jam or encounter an obstacle or due to some other cause be subjected to torsional stress such as will effect shearing of the pin 22, the rotor will stop (but not the governor) and the pressure in governor chamber 23 will immediately drop, such drop being visually indicated on the gauge 127 which is constantly being read by the pilot or operator. The pilot may then immediately turn on the switch 117 and start the boost pump 116, thereby building up the pressure in the chamber 11 to a point where the valve 64 opens and permits fuel to pass from the chamber 11 into the governor chamber 23, the pressure in chamber 23 now being determined by the setting of the spring 125 for the valve 122. Since the pump 116 is controlled independently of the engine, it will replace the engine-driven pump 14, or provide a substitute for the latter, while at the same time the drive on the governor continues through the rotor shaft 19 and cup 36. Thus normal metering will be had irrespective of failure of the pump 14.

Usually, out of precaution, the pilot turns on the boost pump during take-off until the aircraft attains a safe height, such precaution being taken to ensure ample reserve pressure in the fuel system in case the engine should stop momentarily or falter and thereby stop the drive on the engine-driven fuel pump. With the present improved safety device, not only will such action ensure a supply of fuel to the priming system but there will also be full pump pressure on the fuel in the governor chamber in case the pressure in said latter chamber should drop as a result of faulty engine operation, or due to pump failure caused by jamming or seizing of the rotary pump element.

Actual tests show that the efficiency of the

metering system is substantially unaffected by change-over from the engine-driven pump to the boost pump, and also that the emergency system may be operated for long periods of time without material wear and resultant danger of failure of running parts.

It will be understood that no attempt has been made herein to set forth all of the advantages and operating characteristics of the invention, and that the drawings are simply illustrative and that in actual practice it is usually necessary to make certain rearrangements and changes in parts to adapt the invention to different installations, the scope of the invention being limited only by the appended claims.

We claim:

1. In a system for metering fuel to an engine wherein the flow of fuel through a conduit to the engine is regulated by a valve located in the conduit and controlled by an element rotating in synchronism with the engine and to which fuel is supplied through the conduit under pressure by an engine-driven pump provided with a rotor and having a driving connection with said element; means whereby should the rotor of the engine-driven pump fail due to jamming or seizure the drive on said rotating element is maintained, and means supplementing said pump for maintaining a supply of fuel under pressure to said valve.

2. In a system for metering fuel to an engine wherein the flow of fuel through a conduit to the engine is regulated by a valve located in the conduit and controlled by an element rotating in synchronism with the engine and to which fuel is supplied under pressure by an engine-driven pump provided with a rotor and having a driving connection with said element; means whereby should the rotor of the engine-driven pump fail due to jamming or seizure the drive on said rotating element is maintained, and means selectively operable independently of the engine for maintaining a supply of fuel under pressure to said valve.

3. In a system for metering fuel to an engine wherein the flow of fuel through a conduit to the engine is regulated by a valve located in the conduit and controlled by a governor having a drive connection with the engine through an engine-driven fuel pump provided with a pumping element and a driving member therefor; means whereby should the pumping element of the engine-driven pump jam or seize the drive on the governor is maintained through said driving member, and means operable independently of the engine-driven pump for pressurizing the fuel in said conduit upstream of said valve.

4. In a system for metering fuel to an engine wherein the flow of fuel through a conduit to the engine is regulated by a valve located in the conduit and controlled by a governor having a drive connection with the engine through an engine-driven fuel pump provided with a pumping element and a driving member therefor; means whereby should the pumping element of the engine-driven pump jam or seize the drive on the governor is maintained through said driving member, a boost pump operable independently of the engine-driven pump arranged to pressurize the fuel in said conduit upstream of said engine-driven pump, and means for automatically by-passing fuel around said engine-driven pump to said valve when the pressure of the fuel upstream of said latter pump attains a prede-

termined value relatively to the pressure downstream thereof.

5. In a system for metering fuel to an engine wherein the flow of fuel through a conduit to the engine is regulated by a valve located in the conduit and controlled by a governor having a drive connection with the engine through an engine-driven fuel pump provided with a pumping element and a driving member therefor;

10 means whereby should the pumping element of the engine-driven pump jam or seize the drive on the governor is maintained through said driving member, means defining a low pressure intake chamber upstream of the engine-driven pump and a high pressure delivery chamber downstream of the latter, and means operable independently of the engine-driven pump for pressurizing fuel into the delivery chamber when the fuel pressure in said latter chamber drops below a certain value.

6. In a system for metering fuel to an engine wherein the flow of fuel through a conduit to the engine is regulated by a valve located in the conduit and controlled by a governor having a drive connection with the engine through an engine-driven fuel pump provided with a pumping element and a driving member therefor;

25 means whereby should the pumping element of the engine-driven pump jam or seize the drive on the governor is maintained through said driving member, means defining a low pressure intake chamber on the upstream side of said engine-driven fuel pump and a high pressure delivery chamber on the downstream side thereof

30 in communication with said valve, an independently controlled boost pump arranged to pressurize fuel into said intake chamber, and a reverse flow by-pass valve assembly between said chambers, said by-pass valve assembly operating to by-pass fuel from the delivery to the intake chamber under normal periods of operation and to by-pass fuel from the intake to the delivery chamber under emergency periods of operation.

7. For use in a fuel metering system for engines, a fuel metering device including a valve, a governor rotatable in relation to engine speed connected to said valve for controlling the latter, a fuel pump having a pumping element and a drive member therefor adapted to be driven by the engine, means providing a drive connection between the drive member and said governor, and means whereby should the pumping element jam or seize the drive on the governor will be maintained.

8. For use in a fuel metering system for an engine, a fuel metering device having a fuel valve and a governor connected thereto for controlling the valve, a fuel pump adapted to be driven by the engine, said fuel pump including a drive shaft carrying a rotatable pumping element, means providing a driving connection between said shaft and said governor, and means providing a drive connection between said shaft and said pumping element, said latter means being adapted to automatically disconnect the pumping element from the shaft when the torque stress on the rotatable pumping element exceeds a predetermined value.

9. In a system for metering fuel to an engine wherein the flow of fuel through a conduit to the engine is regulated by a valve located in the conduit and controlled by an element rotating in synchronism with the engine and to which fuel is supplied under pressure by an engine-driven

11

pump provided with a pumping element and a driving member therefor having a drive connection with both of said elements, means whereby should the pumping element of the engine-driven pump jam or seize the drive on said rotating element is maintained, means defining a low pressure intake chamber upstream of said engine-driven pump and a high pressure delivery chamber downstream thereof in communication with said valve, a boost pump operable independently of the engine-driven pump arranged to pressurize fuel into said intake chamber in the event of failure of said engine-driven pump, means for bypassing fuel from said intake chamber around said engine-driven pump to the delivery chamber when the pressures in said chambers attain predetermined relative values, and a spring-biased relief valve for said boost pump having a pressure-responsive control element vented to a source of reference pressure changing with changes in pressure in the fuel metering system.

10. In a system for metering fuel to an engine wherein the flow of fuel through a conduit to the engine is regulated by a valve located in said conduit and controlled by an element rotating in synchronism with the engine and to which fuel is supplied under pressure by an engine-driven pump provided with a pumping element and a driving member therefor having a drive connection with both of said elements, means whereby should the pumping element of the engine-driven pump jam or seize the drive on said rotating element is maintained, means defining a low pressure intake chamber on the upstream side of said engine-driven pump and a high pressure delivery chamber on the downstream side thereof in communication with said fuel valve, an independently controllable boost pump arranged to pressurize fuel into said intake chamber, a by-pass valve adapted to bypass fuel from the intake chamber to the delivery chamber around said engine-driven pump when the pressures in said chambers attain predetermined relative values, a relief valve for said boost pump having a pressure-responsive control element vented to the fuel pressure downstream of said fuel valve, and a spring augmenting the pressure of the fuel on said latter element having a spring force substantially equal to the pressure drop across said fuel valve.

11. In a system for metering fuel to an engine wherein the flow of fuel through a conduit to the engine is regulated by a valve located in said conduit and controlled by an element rotating in synchronism with the engine and to which fuel is supplied under pressure by an engine-driven pump provided with a pumping element and a driving member therefor having a drive connection with both of said elements, means whereby should the pumping element of the engine-driven pump jam or seize the drive on said rotating element is maintained, means defining a low pressure intake chamber on the upstream side of said engine-driven pump and a high pressure delivery chamber on the downstream side thereof in communication with said valve, a by-pass valve controlling flow of fuel between said chambers arranged to bypass fuel around said engine-driven pump when the pressures in said chambers attain predetermined relative values, a boost pump arranged to pres-

12

surize fuel into said intake chamber, and means for selectively operating said boost pump.

12. In a system for metering fuel to an engine wherein the flow of fuel through a conduit to the engine is regulated by a valve located in said conduit and controlled by an element rotating in synchronism with the engine and to which fuel is supplied under pressure by an engine-driven pump provided with a pumping element and a driving member therefor having a drive connection with both of said elements, means whereby should the pumping element of the engine-driven pump jam or seize the drive on said rotating element is maintained through said driving member, means defining an intake chamber on the upstream side of said engine-driven pump and a governor chamber on the downstream side thereof in communication with said valve, a by-pass valve between said chambers arranged to bypass fuel around said engine-driven pump when the pressures in said chambers attain predetermined relative values, a boost pump arranged to pressurize fuel into said intake chamber, and means for indicating the pressure in said governor chamber.

13. In a system for metering fuel to an aircraft engine wherein the flow of fuel through a conduit to the engine is regulated by a valve located in said conduit and controlled by a governor rotating in synchronism with the engine and to which fuel is supplied under pressure by an engine-driven fuel pump provided with a pumping element and a driving member therefor having a driving connection with said governor and said element, means whereby should the pumping element of the engine-driven pump jam or seize the drive on said governor is maintained, means defining a low pressure intake chamber on the upstream side of said engine-driven fuel pump and a governor chamber on the downstream side thereof in communication with said valve, a by-pass valve controlling flow of fuel between said chambers and arranged to open when the pressures in said chambers attain predetermined relative values, a fuel tank, an electric boost pump submerged in said tank and arranged to deliver fuel under pressure to said intake chamber, a relief valve for said boost pump having a pressure-responsive control element vented to said fuel conduit upstream of said fuel valve and a spring augmenting the pressure of the fuel having a force substantially equal to the pressure drop across said fuel valve, an electric switch for selectively operating said boost pump, and means for indicating the pressure in said governor chamber.

Certificate of Correction

Patent No. 2,531,664

November 28, 1950

JAY A. BOLT ET AL.

It is hereby certified that error appears in the printed specification of the above numbered patent requiring correction as follows:

Column 10, line 69, for "valve" read *value*; column 11, lines 31 and 60, after "elements" strike out the comma and insert instead a semicolon; line 45, same column, for "valves" read *values*; column 12, line 11, after "elements" strike out the comma and insert instead a semicolon; lines 14 and 15, strike out the words "through said driving member";

and that the said Letters Patent should be read as corrected above, so that the same may conform to the record of the case in the Patent Office.

Signed and sealed this 17th day of April, A. D. 1951.

[SEAL]

THOMAS F. MURPHY,
Assistant Commissioner of Patents.
